WEB CONVEYING MACHINE

George C. Beidler, Rochester, N. Y.

Original application November 30, 1937, Serial No. 177,350. Divided and this application August 18, 1939, Serial No. 290,900

10 Claims. (Cl. 271—2.3)

This invention relates to a machine for drying a web coated on both sides with a sensitized emulsion and has special reference to a feeding and transfer mechanism for such a film or for any other type of web to be carried by a web carrier.

More particularly the present application relates to a division of my prior application for Sensitizing coating machines filed November 30, 1937, Serial No. 177,350, and having matured into Patent No. 2,185,049.

While the term "film" has been used in a generic sense, the invention has its greatest utility in connection with the coating of paper film, since such film has an increased expansive and contractive characteristic compared with other known carriers of emulsion.

It is an object of the invention to provide novel means for applying the film to the carriers or the segments which are provided with pins for impaling or impinging the film, and novel means, as stated, are provided for pressing the paper on the pins and then freeing the carriers with the film attached thereto; the said impaling instrumentality being also associated with means for operating the film tensioning device associated, in this embodiment of the invention, with the stick and the aforesaid segmental supports.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates an edge elevation of one of the main feed rolls and the parts carried thereby;

Figure 2 illustrates an edge view of a portion of a main feed roll showing a part of the edge not disclosed in Fig. 1;

Figure 3 illustrates a section on the line 3—3 of Fig. 2;

Figure 4 illustrates a face view of the main feed roll with the parts carried thereby and also showing auxiliary feed rolls associated with the main roll;

Figure 5 illustrates a side elevation of a cover plate shown in Figs. 1 and 4 and disclosing the manner in which the plate is secured;

Figure 6 illustrates a side elevation of a cer-

tain camming roll and its bracket as shown in Fig. 4;

Figure 7 illustrates a section on the line 7—7 of Fig. 1;

Figure 8 illustrates a section on the line 8—8 of Fig. 7;

Figure 9 illustrates an edge view of a certain eccentric ring and blade disclosed in Fig. 7;

Figure 10 illustrates an edge view of a portion of one of the main feed rolls showing a certain paper web clipping or holding means and part of its operating mechanism;

Figure 11 illustrates a section through the feed roll of Fig. 10 and showing an elevation of the clipping means and operating mechanism at right angles to the manner in which the parts are shown in Fig. 10;

Figure 12 illustrates a section on the line 12—12 of Fig. 10;

Figure 13 illustrates a detail section on the line 13—13 of Fig. 4;

Figure 14 illustrates a detail section on the line 14—14 of Fig. 1, but in the opposite direction to the arrows on said line;

Figure 15 illustrates an enlarged section on the line 15—15 of Fig. 14;

Figure 16 illustrates a face view of a certain cam used in connection with a main feed roll;

Figure 17 illustrates a side view of the cam shown in Fig. 16;

Figure 18 illustrates a second side view of said cam at right angles to Fig. 17;

Figure 19 illustrates a developed diagram of said cam;

Figure 20 illustrates a plan view of one of the main feed rolls and the parts adjacent thereto;

Figure 21 illustrates a side elevation of certain of the parts shown in Figure 20, the view disclosing the driving means and a rocking bracket used in the invention;

Figure 22 illustrates a fragmentary section on the line 22—22 of Figure 20 and showing the gearing connecting certain shafts; and

Figure 23 illustrates an enlarged showing in side elevation of a certain means used herein to effect tripping of a latch to start the main feed roller rotating.

Figure 24 is a fragmentary detail showing the relation of the device shown in Figures 1 to 23 to a stick and its runway or supporting rail.

The sticks used in connection with this invention are supported on a pair of inclined rails A and are moved by driven chains (not shown) upwardly along the rails.

Each of the sticks C is provided at each end

with a supporting block or slide 12 which is supported on and travels along a rail A. These slides 12 are connected by a transverse rod having a central portion 13 rounded on one side and having angularly disposed faces on the other side. This central portion merges at its ends into octagonally prismatic portions 14 which again merge into portions 15.

Fixed to one octagonal portion 14 of the stick, 10 at one of its ends, is an arcuate paper support 25 having outwardly projecting radial prongs 26.

The main feed rolls are each supported on a shaft 41 carried by one arm of a bell crank bracket 42 and these rolls are located at the right 15 and left ends of the shaft 41 respectively, it being understood that the apparatus forming the subject matter of the present application is duplicated in the complete machine as is shown in my copending application Serial No. 177,350. Re- 20 volably mounted on the shaft 41 is a sleeve 42' whereon is fixed a sprocket 43 driven by a chain 44. Splined on the sleeve 42' is a sleeve 44' whereon is revolvably mounted the main feed wheel 45, the sleeve 42' extending entirely through 25 the sleeve 44' and thus projecting through the wheel 45. Fixed on the projecting end of the shaft 41 is a cam 46 having the face adjacent the wheel 45 provided with a high segment 47, an intermediate segment 48 and a low segment 49. 30 Fixed on the wheel 45 is a bracket 50 carrying a cam roller 51 which bears constantly on the cam face, being held thereagainst by a spring 52 surrounding the sleeve 42' between the sprocket 43 and the adjacent end of the sleeve 44'. While 35 the wheel 45 is revolvably mounted on the sleeve 44', a ratchet 53 is fixed on this sleeve and revolves therewith as the sprocket is actuated, the latter rotating constantly during the operation 40 of the machine. Pivoted on the wheel 45 is a pawl 54 urged by a spring 55 into engagement with the ratchet 53. A stop 56 engages the pawl tail 57 upon each complete revolution of the wheel 45 and causes it to disengage from the ratchet 53, the extent of disengagement being 45 limited by a stop 58 fixed on the wheel 45.

The paper web P is fed at each edge down chains 59 each passing around a sprocket 60. These sprockets 60 are mounted on a shaft 60a extending across the machine and suitably supported at each side thereof. The brackets 42 are 50 rockingly mounted at their angles on the shaft 60a. The chains 59 are provided at intervals with paper engaging pins 59a. From the chains 59 the web P passes over an auxiliary roller 61 and a 55 second and smaller roller 62. This auxiliary roller has a sponge rubber periphery 61a. Since the timing of the parts is such that the movement of the stick C is slower than the peripheral speed of the wheel 45, in order that loops or bights may 60 be formed between the successive sticks, the paper must continue to feed past the wheels 45 while they are at rest. Also, the wheels 45 revolve intermittently and for these reasons it is necessary that the paper during stoppage of the wheels 45, 65 shall roll freely over the rollers 61 and 62 so that the paper will not be gripped between them and the wheel 45, there is mounted on the rear face of the wheel 45 a set of pins 63 which are disposed at 70 the angles of an equilateral triangle and are so positioned that the center of a circle circumscribed about these pins and tangent thereto will be disposed eccentrically to the center of the wheel. As best shown in Fig. 8, there is mounted 75 on each of these pins a revoluble sleeve 64 and a

spacing sleeve 65 is mounted on each pin to rest against the wheel 45, the spacing sleeves terminating in spaced relation to the ends of the sleeves 64. On the projecting ends of the sleeves 64 is mounted a ring 66 which is thus supported 5 as an eccentric strap, the sleeve and pin arrangement forming an eccentric embraced by this strap. The ring or strap 66 is held in position on the sleeves 64 by caps 67 secured to the ends of the pins 63 by screws 68. Attached to the ring 66 is a 10 bracket 69 which carries an eccentric blade or rod 70. Swingingly mounted on a frame rod 71 is an arm 72 carrying a stub shaft 73 whereon the roller 61 is revolvably mounted. On the blade 70 adjacent its free end is a sleeve 74 wherein the stub 15 shaft 73 is slidably mounted so that the lateral movement of the wheel 45 relative to the roller 61 may be effected. On the stub shaft is mounted a lever 75, one arm of which is connected to swing on the shaft 76a by a swinging link 76 pivoted to 20 said arm at one end having its other end mounted on a fixed pivot 76a. The other arm of the lever 75 has pivoted thereto an arm 77 which is held in normal alignment with the lever 75 by a spring 78. This arm carries at its free end the roller 62. 25

With this arrangement the eccentric acts, as the wheel 45 rotates, to alternately move the rollers toward and from the wheel 45.

In order to grip the paper firmly between the wheel 45 and the paper supports 25 as they pass 30 beneath the wheel and also to allow for the movement of the sticks slower than the wheel, there is provided a pocket 79 formed in the periphery of the wheel and extending arcuately therearound. In this pocket is fitted an arcuate slide 80 of channel shape in cross section and the channel is filled 35 with an arcuate mass 81 of sponge rubber which, as shown in Figs. 2 and 3, normally projects beyond the periphery of the wheel 45. The slide is normally held at what may be termed the forward 40 or advancing end of the pocket by springs 82 which have their forward ends fixed to posts 83 projecting from the members 45 and their rear ends fixed to brackets 83' by screws 84 passing to the slide through arcuate slots 85 formed in the 45 side faces of the wheel 45, as shown in Fig. 4. The movement of the sticks and the rotation of the wheel 45 are so timed that a paper support 25 engages the forward end of the mass 81 at each revolution of the wheel 45. As the wheel 45 has a 50 greater peripheral speed, due to the member 25 on the stick elevating the wheel shown in Fig. 24, than the lineal speed of the sticks, the continuance of the rotation of the wheel causes the latter to move faster than the mass can move, so that 55 the wheel advances to cause the slide to be engaged by the rear end of the pocket 79. Then, as the stick passes clear of the arcuate mass, the springs which have been tensioned by the movement just described, retract the slide to its normal 60 position. It will be noted that the screws 84 serve to hold the slide in its pocket.

At a certain part of the revolution of the wheel, it is desirable to hold the edge of the paper web 65 close to the periphery of the wheel 45 while, during the remainder of the revolution, it is desirable that the paper web be free from the wheel. The paper web is held from the time it leaves the feed chains 59 until it is engaged on 70 the stick after which it is freed. To accomplish this, there is provided a plunger 86 which passes through the wheel from side to side and projects at each side. On the outer side of the wheel this plunger carries a head 87 which supports a finger 75

88 extending across the peripheral face of the wheel closely adjacent thereto. The function of this finger is to engage the outer surface of a portion of the paper web P in contact with the wheel when said finger is in position across the wheel. The other end of the plunger carries a rack 89 on the end of which is fixed a bracket 90 which supports one end of a coiled compression spring 91 having its end supported by the wheel 45. This spring urges the finger to operative position (Fig. 10). The rack 89 meshes with a gear 92 fixed on a shaft 93 journaled in a bracket 94 fixed to the front face of the wheel 45. A bracket 95 may also aid in supporting the shaft 93. On the shaft 93 is fixed an operating lever 96 which normally extends angularly forward with reference to the direction of rotation of the wheel from the shaft 93. The shaft 41 is provided with a head 97 (Fig. 4) to which there is fixed a plate 98 carrying an arm 99. This arm supports a blade 100 which lies in the path of the lever 96 as the wheel 45 rotates. When the lever 96 engages the blade 100, the rotation of the wheel causes the lever to swing in an anti-clockwise direction as viewed in Fig. 4 and this, through the gear and rack, retracts the finger 88, as shown in dotted lines in Fig. 10. As soon as the lever 96 passes the blade 100, the spring 91 returns the finger to normal position. This retraction of the finger occurs just at that point in the revolution of the wheel at which the finger approaches the paper web P. The return to normal occurs as soon as the finger passes the plane of the paper web so that the finger then engages the paper web and holds it to the periphery of the wheel. On the plate 98 is fixed a bracket 101 (Fig. 4) which supports a fixed shaft 102 whereon is pivoted an end of arm 103, the shaft being eccentric to the axis of the wheel 45. The plate 98 carries a stop 104 against which the arm is normally held by a spring 105. A stop 106 limits movement of the arm 103 against the action of the spring 105. This arm carries a blade 107 which is in sliding and overlapping contact with a blade 108 mounted on a fixed bracket 109. The blades 107 and 108 lie in the path of the lever 96 which is operated to retract the finger 88 by the action of the blade 100. On the front face of the wheel 45 is fixed a post 110 which, by the revolution of the wheel, engages the back of the blade 107 and moves it against the action of the spring 105. Due to the eccentricity of the pivot shaft 102, after the post 110 has moved the blade 107 a certain distance, the blade will ride over the post and, by action of the spring 105, will return to normal position. The post 110 is so positioned in relation to the shaft 93 that upon the blade 107 being released from the post, this blade will engage and quickly turn the lever 96 to finger-retracting position, thus releasing the paper web. The lever 96 will continue in finger-retracting position until it rides off the blade 108, whereupon it will be returned to normal position by the action of the spring 91.

Provision is made to keep the paper web from slipping during the first part of its engagement by the finger 88 so that it cannot accidentally slide from between the finger and wheel 45. To this end, the wheel 45 is provided, adjacent the finger 88, with a radial bore 111 wherein is mounted a plunger 112 carrying a needle 113. The outer end of this bore is closed by a needle guide 114 and the needle is held normally re-

tracted by a spring 115 (Fig. 12). In the plunger 112 is provided an opening 116 wherein is fitted the end of a pin 117 projecting through a slot 118 formed in the front face of the wheel 45. This pin is supported by the free end of an arm 119 pivotally mounted on a bracket 120 on the front face of the wheel 45 and the pin projects from the arm and carries a cam roller 121 (Figs. 11 and 13). On the cam 122 is a camming lug 122 which projects peripherally from the cam and is positioned to be engaged by the cam roller 121 just before the lever 96 passes off of the blade 100. By this engagement the needle is projected and passes through the paper web to hold the latter from slipping until the roller 113 engages 15 and grips the paper web. The timing of this part of the device is such that the needle 113 remains engaged with the paper until the stick passes beneath the wheel 45 and engages the paper. The roller 121 then passes from the cam 20 lug 122 and the spring 115 again retracts the needle.

By reference to Figs. 20, 21 and 22, it will be seen that, while one arm of the bell crank 42 carries the shaft 41, the other arm has a shaft 25 123 fixed therein. As shown best in Fig. 21, the shaft 123 has a sprocket 124 mounted thereon and the chain 44 extends around the sprocket 124 as well as the sprocket 43. It will be noted that in Fig. 21 many parts are omitted in order 30 to show the arrangement of the remaining parts without confusion. On the shaft 123 is also mounted a gear 125 which is connected to the sprocket 124 by screws 126 passing through spacing sleeves 127. A collar 128 serves to hold the 35 sprocket 124 and gear 125 on the shaft 123. It will be seen in Fig. 20 that there are two sprockets 60. One of these sprockets 60 is connected by screws 129 and spacers 130 with a gear 131 mounted on the shaft 60a and meshing with the 40 gear 125. By this means the shaft 41 is constantly driven even when the wheel 45 is raised by the stick passing beneath it.

Mounted on each side rail is a bracket 132 to which is pivoted one end of a trip arm 133. This 45 arm lies in the path of the sticks C so that as each stick moves along the rail A it passes beneath and lifts the arms 133. A clamp 134 secures the sheath 135 of a Bowden wire 136 to the bracket 132. The wire 136 is secured to the 50 arm 133 as by a screw 137. The remaining end of the sheath is secured by a clamp 138 to an arm 139 carried by a bracket 140 fixed to the bell crank 42. The latch arm 56 is pivoted to the bracket 140 as at 141 so as to form a two- 55 armed lever, one arm of which normally engages the pawl tail 57. The Bowden wire 136 is secured to the remaining arm of this lever by a screw 142. A spring 143 connects this last arm and the bracket 140 so that the latch arm 56 is constantly urged into position to engage the tail 57.

Normally the wheels 45 are at rest, but as a stick C passes the trip arms 133, these arms lift and push on the Bowden wire so that the latches 65 56 are freed from the pawl tails 57 and the pawls 54 engage the constantly rotating ratchets 53 and the wheels 45 start to rotate. As soon as the stick C passes from beneath the trip arms 133, these arms are free to fall and the springs 143 act to 70 restore the latch 56 to pawl tail engaging position so that upon the completion of one revolution of the wheels 45, the pawls 54 are disengaged from the ratchets 53 and the wheels 45 cease to move. Thus the sticks are moved in succession beneath 75

the trip arms 133 and then beneath the wheels 45. As the sticks are thus moved, each wheel 45 is intermittently engaged, by the action of the trip lever, to its continuously revolving ratchet 53, 5 each engagement causing one complete revolution of the wheel. As the wheel rotates, the finger 88 is first retracted and then released to engage the paper web as it is fed to the wheel. As soon as engagement is effected, the needle 113 is actuated to pierce and hold the paper web until it is engaged by the roller 61 through the action of the eccentric strap 66. The finger 88 continues to hold the paper web until the edge of the paper web is gripped between the stick and the arcuate mass 84, after which the blade 107 acts to retract the finger 88 and release the paper web which is now draped over the stick. Further movement of the wheel 45 restores all parts thereon to normal position and the wheel temporarily ceases to 10 revolve so that a proper length of paper web may be fed from the feed chains to form a bight before the next stick arrives beneath the wheel 45.

I claim:

1. In a web conveying machine, a feed wheel 25 having a periphery engaged by film which it feeds, a member transversely reciprocable in the said feed wheel, a finger supported on said member at one side of the wheel, the said finger extending transversely of the wheel, a rack on the 30 said member, a pinion engaging the rack, means for operating the pinion to move the rack in one direction, and resilient means for imparting movement to the rack in the opposite direction.

2. In a web conveying machine, a main feed 35 roller, a second roller mounted for motion toward and from the main feed roller, said rollers being arranged to grip opposite faces of the web between them upon the second roller being moved toward the main feed roller, cam means carried by and 40 rotating with said main feed roller, and a linkage connecting said cam means and the second roller for moving said second roller into and out of web gripping position.

3. In a web conveying machine, a main feed 45 roller, a second roller mounted for motion toward and from the main feed roller, said rollers being arranged to grip opposite faces of the web between them upon the second roller being moved toward the main feed roller, a series of posts projecting from one face of said main feed roller and 50 arranged with their axes in a circle eccentric to the axis of said main feed roller, an eccentric strap surrounding said posts, and an arm connecting said strap and the second roller whereby to effect movement of the second roller toward and from the first roller.

4. In a web conveying machine, a main feed 60 roller, a second roller, means to support said second roller, for swinging movement toward and from the first roller and including a stub shaft whereon said second roller is journalled, a series of posts extending from one face of the main feed roller and arranged with their axes on a circle eccentric to the axis of the main feed roller, sleeves 65 mounted revolvably on said posts, an eccentric strap surrounding the series of posts and sleeves and engaging the peripheral surfaces of all of said sleeves, and an arm extending radially from said eccentric strap and having an opening in its outer end receiving a portion of said stub shaft.

5. In a web conveying machine, a main feed 70 roller, a second roller mounted for motion toward and from the main feed roller, said rollers being arranged to grip opposite faces of the web between them upon the second roller being moved toward

the main feed roller, a series of posts projecting from one face of said main feed roller and arranged with their axes in a circle eccentric to the axis of said main feed roller, an eccentric strap surrounding said posts, an arm connecting 5 said strap and the second roller whereby to effect movement of the second roller toward and from the first roller, and means to cause single complete revolutions of said main roller at spaced time intervals. 10

6. In a web conveying machine, a main feed roller, a second roller, means to support said second roller for swinging movement toward and from the first roller and including a stub shaft whereon said second roller is journalled, a series 15 of posts extending from one face of the main feed roller and arranged with their axes on a circle eccentric to the axis of the main feed roller, sleeves mounted revolvably on said posts, an eccentric strap surrounding the series of posts and 20 sleeves and engaging the peripheral surfaces of all of said sleeves, an arm extending radially from said eccentric strap and having an opening in its outer end receiving a portion of said stub shaft, and means to cause single complete revolutions 25 of said main roller at spaced time intervals.

7. In a web conveying machine, a main feed roller, a second roller mounted for motion toward and from the main feed roller, said rollers being arranged to grip opposite faces of the web between them upon the second roller being moved toward the main feed roller, a series of posts projecting from one face of said main feed roller and arranged with their axes in a circle eccentric to the axis of said main feed roller, an eccentric strap surrounding said posts, an arm connecting 30 said strap and the second roller whereby to effect movement of the second roller toward and from the first roller, a hollow shaft whereon said main roller is revolvably mounted, means for continuously rotating said hollow shaft, a ratchet fixed to said hollow shaft and resting against one side face of said roller, a pawl carried by said main roller and spring urged into engagement with said ratchet, a dog in the path of said pawl 35 spring urged to engage said pawl and hold it from engagement with said ratchet, and means acting at intervals to move the dog out of said path to free said dog temporarily from said pawl and arranged to allow the dog to return to said 40 path upon engagement of the ratchet by the pawl. 45

8. In a web conveying machine, a main feed roller, a second roller, means to support said second roller for swinging movement toward and from the first roller and including a stub shaft 55 whereon said second roller is journalled, a series of posts extending from one face of the main feed roller and arranged with their axes on a circle eccentric to the axis of the main feed roller, sleeves mounted revolvably on said posts, an eccentric strap surrounding the series of posts and sleeves and engaging the peripheral surfaces of all of said sleeves, an arm extending radially from said eccentric strap and having an opening in 60 its outer end receiving a portion of said stub shaft, a hollow shaft whereon said main roller is revolvably mounted, means for continuously rotating said hollow shaft, a ratchet fixed to said hollow shaft and resting against one side face of 65 said roller, a pawl carried by said main roller and spring urged into engagement with said ratchet, a dog in the path of said pawl spring urged to engage said pawl and hold it from engagement with said ratchet, and means acting at 70

75

intervals to move the dog out of said path to free said dog temporarily from said pawl and arranged to allow the dog to return to said path upon engagement of the ratchet by the pawl.

- 5 9. In a web conveying machine, a main feed roller, a second roller mounted for motion toward and from the main feed roller, said rollers being arranged to grip opposite faces of the web between them upon the second roller being moved
- 10 toward the main feed roller, means actuated from the main feed roller for moving the second roller between web gripping and web releasing positions, means to cause single complete revolutions of said main roller at spaced time intervals, a
- 15 prong mounted for radial movement in said main feed roller and having an outer end projecting from the periphery of said main roller in one position and retracted within the roller in a second position, spring means urging said prong to re-
- 20 tracted position, an operating lever operatively connected to said prong for moving said lever to protracted position, said lever being pivotally carried by said main roller to revolve therewith, and means fixed in the path of said lever to move the lever at one point in the revolution of said

main roller and thereby to cause protraction of the prong.

- 10 10. In a web conveying machine, a main feed roller, a second roller mounted for motion toward and from the main feed roller, said rollers being arranged to grip opposite faces of the web between them upon the second roller being moved toward the main feed roller, means actuated from the main feed roller for moving the second roller between web gripping and web releasing positions, means to cause single complete revolutions of said main roller at spaced time intervals, a finger normally extending across the periphery of the main feed roller in closely spaced relation thereto, means to mount said finger on said main 15 roller for sliding movement transversely of said periphery, spring means urging said finger to normal position, a lever operatively connected to said finger mounting means for moving said finger clear of said periphery, said lever being 20 pivotally supported on the main roller remote from the axis thereof, and means fixed in the path of said lever to engage and actuate the lever as the main roller rotates.

GEORGE C. BEIDLER. 25
